UNITED STATES PATENT OFFICE.

LETITIA BINGHAM MC EWEN, OF NEW YORK, N. Y., ADMINISTRATRIX OF
JOHN MC EWEN, DECEASED.

CLAMP FOR ROPES.

SPECIFICATION forming part of Letters Patent No. 631,938, dated August 29, 1899.

Application filed January 10, 1898. Serial No. 666,234. (No model.)

To all whom it may concern:

Be it known that I, LETITIA BINGHAM MC EWEN, a citizen of the United States, and a resident of New York, (Brooklyn,) county of 5 Kings, and State of New York, administratrix of the estate (as will more clearly appear by reference to the duly-certified copy of the letters of administration hereunto annexed) of JOHN MC EWEN, deceased, late of Brooklyn, county of Kings, and State of New York, who did invent certain new and useful Improvements in Clamps for Ropes, declare that the following is a specification of said invention, reference being had to the accompanying drawings, forming a part thereof, in which similar letters of reference indicate corresponding parts.

This invention relates to an improved clamp for ropes, its object being to provide a simple, durable, and economic device whereby two ropes or two parts of one rope may be quickly and firmly bound together and as quickly released. It is peculiarly fitted for use upon guy-ropes of derricks, tent-poles, 25 and flag-staffs, but may be used upon clothes-lines or in lieu of a seizing upon any rope.

The invention consists, primarily, of a cam-lever in connection with clamping-jaws, and will be hereinafter fully described, and specifically set forth in the annexed claim.

In the accompanying drawings, forming part of this specification, Figure 1 is a side elevation of the device, showing it in operative position upon a guy-rope. Fig. 2 is a 35 side elevation, partly sectional, showing the clamp in position when in use. Fig. 3 is a vertical section of the clamp on line xx of Fig. 2.

In the practice of the invention a frame 40 may be employed having two parallel side walls A A' and end wall B, formed integrally from wrought iron or steel preferably. The walls A A' near the open or free end C have apertures in which a headed pivot-bolt a is secured. A cam-lever D, having an arm d extended therefrom, is mounted on said pivot, and upon the free end of said arm is secured 45 an eyebolt or loop d' , projecting at a right angle therefrom.

In the inner end of the casing are loosely inserted two clamping-jaws, the inner one b

of which is fluted or serrated on each face thereof, the outer one b' being similarly fluted or serrated upon its inner face, the outer face being plane, and against which the cam-lever 55 bears. Said jaws b and b' are provided at one end with T-shaped heads b^2 and b^3 , respectively, adapted to prevent them from being drawn between the side walls A and A' by the strain upon the rope. The end wall B of the 60 casing is also fluted or serrated upon its inner surface.

In operation the end of the rope F is inserted from above in the eye d' , passed between the end wall B and the inner jaw b , 65 then around the post E and back between the two movable jaws b and b' . The cam is then moved against the clamp by means of the arm, and the clamps grip the inclosed rope firmly between them and in such a manner that it cannot be moved except by reversing the cam.

It is obvious that a cam-lever of different design from that shown may be used, also that the eyebolt d' may be riveted to or formed 75 integrally with the lever-arm d . A hook may be substituted for said eyebolt. The movable jaws may have T-heads upon both ends thereof, preventing withdrawal in either direction.

Having thus described the invention, what 80 is claimed as new, and desired to be secured by Letters Patent, is—

An improved rope-clamp of the class described, adapted for the duplex clamping and adjustment of two strands of a rope bight, 85 comprising the slideable frame embodying the opposite side walls and the end wall, the clamping plates or jaws inclosed between said side walls and having an adjustable sliding operation within said frame with relation to the end wall, means for preventing 90 a front-and-rear movement of said plates or jaws between the side walls by the strain upon the rope, and a cam-lever fulcrumed between said side walls below the plate or 95 jaws and adapted to tighten the latter, said cam-lever having an extended rearwardly-projecting arm projecting to a position with relation to the main strand of the rope bight and carrying a device adapted to engage 100 with said main strand, whereby the main strand of a rope bight can be first passed

through the frame and then turned and its end strand passed also through the frame and the multiple clamping mechanism will operate in a duplex manner to secure both strands 5 and retain the bight taut, substantially in the manner and as set forth.

In testimony that I claim the foregoing as the invention of JOHN MCEWEN, deceased, I

have signed my name, in presence of two witnesses, this 5th day of January, 1898.

LETITIA BINGHAM MCEWEN,
*Administratrix of the estate of John McEwen,
deceased.*
